UNITED STATES PATENT OFFICE.

CARL RONDELL, OF STILLWATER, MINNESOTA.

DESIGN FOR A MARINE PROPELLER.

SPECIFICATION forming part of Design No. 33,386, dated October 16, 1900:

Application filed June 7, 1900. Serial No. 19,472. Term of patent 14 years.

To all whom it may concern:

Be it known that I, CARL RONDELL, a citizen of the United States, residing at Stillwater, in the county of Washington and State of Minnesota, have invented and produced a new Design for a Marine Propeller, of which the following is a specification.

In the accompanying drawings, Figure 1 is a plan view of my propeller; and Fig. 2, a transverse section, showing a face view of the propeller.

My design is embodied in the form or shape

of the blades A and in their arrangement around the cylindrical hub B—that is to say, the blades A are set spirally on the hub B and their forward edges α are straight, while the outer ones α' are convex, as shown.

What I claim is—

The design for a marine propeller, as shown and described.

CARL RONDELL.
